UNITED STATES PATENT OFFICE.

NATHAN KASE, OF BROOKLYN, NEW YORK, ASSIGNOR TO KASE-QUINBY RUBBER COMPANY, INC., A CORPORATION OF NEW YORK.

DESIGN FOR A BOX OR SIMILAR CONTAINER.

Application filed February 25, 1926. Serial No. 16,656. Term of patent 7 years.

To all whom it may concern:

Be it known that I, NATHAN KASE, a citizen of the United States of America, residing in the borough of Brooklyn, county of Kings, city and State of New York, have invented a new, original, and ornamental Design for Boxes or Similar Containers, of which the following is a specification, reference being had to the accompanying drawing, forming a part thereof.

The figure is a perspective view of a box or similar container illustrating my new design.

I claim:

The ornamental design for a box or similar container substantially as shown.

This specification signed this 18 day of February, 1926.

NATHAN KASE.
